UNITED STATES PATENT OFFICE.

DOROTHY LEE, OF LOS ANGELES, CALIFORNIA.

DESIGN FOR A PLACE CARD FAVOR.

Application filed June 23, 1925. Serial No. 13,864. Term of patent 3½ years.

To all whom it may concern:

Be it known that I, DOROTHY LEE, a citizen of the United States, residing at Los Angeles, in the county of Los Angeles and State of California, have invented a new, original, and ornamental Design for Place Card Favors, of which the following is specification, reference being had to the accompanying drawing, forming part thereof.

The place card favor is made of paper with the exception of the pedestal and upright supporting the figure.

I claim:

The ornamental design for a place card favor, as shown.

DOROTHY LEE.
